UNITED STATES PATENT OFFICE.

JOHN BRANDT, OF CHICAGO, ILLINOIS.

HEAD-PIECE FOR STRINGED INSTRUMENTS.

SPECIFICATION forming part of Letters Patent No. 609,531, dated August 23, 1898.

Application filed January 19, 1898. Serial No. 667,168. (No model.)

To all whom it may concern:

Be it known that I, JOHN BRANDT, a citizen of the United States, residing in the city of Chicago, in the county of Cook and State of Illinois, have invented a new and useful Improvement in Head-Pieces for Stringed Instruments, of which the following is a specification.

My invention relates to improvements in head-pieces for mandolins, banjos, guitars, violins, and other like stringed instruments; and the objects of my invention are, first, to provide a head-piece for such instruments, having tuning-pegs actuated by worm-gearing, in combination with such mechanism that the parts will be so firmly held that they will not rattle, and, second, to provide a head-piece that will occupy a narrow space and that may be placed on the upper side of the head of the neck of the instrument instead of upon the under side thereof. I attain these objects by the mechanism illustrated in the accompanying drawings, in which—

Figure 1 is a top view of my improved head-piece attached to the head of the neck of the instrument. Fig. 2 is a side view of the flanges on the plate which bears the worm-gearing and by means of which the head-piece is attached to the neck of the instrument. Fig. 3 is a view of the interior of my device, showing the worm-gearing and the central notched head-stock for the spindles and also the additional plate to which the tuning-pegs are clamped. Fig. 4 is a side view of the notched head-stock. Fig. 5 is an enlarged section of the device, taken on the line 5 5, Fig. 1. Fig. 6 is an enlarged section of the device, taken on the line 6 6, Fig. 3.

Similar letters refer to similar parts throughout the several views.

In the drawings, A represents the upper side of a plate having thereon the sides or flanges B on each side thereof and apertures a a therein for the reception of the tuning-pegs b b.

Apertures c c are made in the flanges B to receive and form a bearing for the spindles c' c' c', which bear the worms d d d. To the outer extremities of the spindles c' c' c' are firmly attached, by riveting or otherwise, the thumb-pieces c² c² c², by which said spindles are actuated. The inner extremities of the

spindles c' c' c' have attached thereon the heads e e, which heads are so arranged that there is a space or groove e' between each of 55 said heads and the inner extremity or bearing d' of the worm d. The head-stock f is a narrow plate, having flanges f' f', one at each side thereof, with rounded notches f² f² f² formed therein. Said grooves e' e', formed 60 between the heads e e on the spindles c' c' and the inner extremities or bearings d' d' of the worms d d, fit snugly into the notches f² f², but not so as to bind said spindles.

The pegs b b b, with rounded tops tapering 65 inward toward the base thereof, as shown, have apertures b' b' therein for the reception of the strings b² b² of the instrument, said strings being fastened to said pegs in the usual manner. The pegs b b b are arranged 70 in rows on each side of the head-piece longitudinally in a straight line with each other, as shown. Said pegs b b b have each attached to the under part thereof a gear g by means of a screw g', which extends through said gear 75 and into the peg b. Said pegs are squared at their lower extremities, as shown at b⁴, to receive the screws g' and are rounded at their part next to said square part, as shown at b⁵, to fit snugly, but not so as to bind into 80 the apertures b³ in the plate h. Next to the rounded part b⁵ on the pegs b is an enlarged rounded portion b⁶, forming a shoulder which fits snugly, but not so as to bind into the apertures a a in the flanged plate A. This 85 shoulder b⁶ tapers slightly, as shown, to correspond with a taper in the aperture a, so that the adjustment of said shoulder b⁶ with aperture a is close and exact. This shoulder b⁶ being of greater diameter than the aperture b³ in the plate h, the attachment of the gear g to the peg b clamps the plate h between the shoulder b⁶ and the gear g.

The plate h is rectangular and of proper size and shape to fit closely between the flanges 95 B of the plate A. Said plate h covers a sufficient space on the plate A to bear all the pegs b b b, gears g, and worms d d.

The plate h being prepared by being clamped between the gears g g and shoulders 100 b⁶ b⁶ on the pegs b b, the heads of the pegs b are passed through the apertures a a in the flanged plate A. The spindles c' c', bearing their worms d d, are inserted through

the apertures c c in the flanges B in two rows, one on each side of the plate, the worms d d and heads e e being inside the flanges B B, the outer extremities of the spindles project-
 5 ing outside said flanges to bear the thumb-
 pieces c^2 c^2 . The grooves e' e' between the
 heads e e and the bearing d d are fitted into
 the notches f^2 f^2 in the flanges f' of the head-
 stock f and the head-stock f tightly fastened
 10 to the plates A and h by rivets m m. The
 flanges f' f' of the holder f also bear against
 the gears g g, so as to prevent them from rat-
 tling. The spindles, worms, gears, and pegs
 are by this arrangement held so snugly in
 15 their proper positions that any rattling is im-
 possible.

The head-piece is fitted upon the head of
 the neck H of the instrument, which is hol-
 lowed out to receive the parts, and the head-
 20 piece is held in position by screws n n through
 the holes n' n' in the flanges B.

My improved head-piece being capable of
 being made narrow, the head of the neck of
 the instrument may be made correspondingly
 25 narrow. The head, therefore, takes up less
 room than the old form of head and is less
 clumsy, and the case in which it is placed may
 be much smaller than those usually made.

My head-piece is adapted to be placed upon
 30 the upper side of the head of the neck of the
 instrument instead of underneath said head,
 as head-pieces are now usually placed.

When the head-piece is placed upon the
 upper side of the head of the neck of the in-
 strument, the pegs do not pass through the
 35 head, and therefore do not slip or get loose
 and rattle, as pegs which pass through the
 head are liable to do. The instrument is also
 more convenient to handle and has a better
 40 tone than instruments having any form of
 head now in use.

What I claim as new, and desire to secure
 by Letters Patent, is—

1. In a head-piece for stringed instruments,
 45 the combination of a plate having two flanges;
 rotary pegs arranged on each side of said
 plate in two rows longitudinally thereof; a
 head-stock arranged lengthwise of said plate,
 between said two rows of pegs, and consist-
 50 ing of a channeled plate having perforations
 or notches in the sides thereof; spindles,
 bearing worms, and having a bearing in one
 of the flanges on said flanged plate, and held,
 at their inner extremities, by said head-stock;
 55 and gears on said pegs to engage with the
 worms on said spindles, all substantially as
 described.

2. In a head-piece for stringed instruments,
 the combination of a plate having two flanges;
 60 rotary pegs, whose longitudinal center line
 is at right angles to said plate, and arranged
 on each side of said plate in two rows longi-
 tudinally thereof; a head-stock arranged
 lengthwise of said plate between said two
 65 rows of pegs, and consisting of a channeled
 plate having perforations or notches in the
 sides thereof; spindles, bearing worms, and

having a bearing in one of the flanges on said
 flanged plate, and held at their inner extremi-
 ties by said head-stock; and gears on said 70
 pegs to engage with the worms on said spin-
 dles, all substantially as described.

3. In a head-piece for stringed instruments,
 the combination of a plate having two flanges;
 rotary pegs whose longitudinal center line is 75
 at right angles thereto, and arranged on each
 side of said plate in two rows longitudinally
 thereof; a head-stock arranged lengthwise
 of said plate between said two rows of pegs,
 and consisting of a channeled plate, having 80
 notches in the sides thereof; spindles having
 a bearing in one of the flanges of said plate,
 and carrying worms to engage with gears on
 said pegs; heads on the inner end of said
 spindles; grooves between said heads and the 85
 inner extremity of said worms; the groove on
 said spindles fitting into said notches in said
 head-stock, whereby said spindles are firmly
 held, all substantially as described.

4. In a head-piece for stringed instruments, 90
 the combination of a flanged plate, an addi-
 tional plate in contact with said flanged plate;
 a rotary peg extending through an aperture
 is said additional plate; a gear attached to
 said peg; a shoulder on said peg, said shoul-
 95 der and said gear being of greater diameter
 than the aperture in said additional plate,
 whereby said additional plate is clamped be-
 tween said gear and said shoulder; an aper-
 ture in said flanged plate, adapted to receive 100
 and fit said shoulder on said peg, the head of
 said peg extending beyond, and the longitudi-
 nal center line of said peg being at right
 angles to said flanged plate, means for oper-
 ating said gears, and means for attaching 105
 said additional plate to said flanged plate; all
 substantially as described.

5. In a head-piece for a stringed instrument,
 the combination of a plate having two flanges;
 a head-stock arranged lengthwise of said 110
 plate, and consisting of a channeled plate hav-
 ing notches in the sides thereof; spindles car-
 rying worms, and having a bearing in one of
 the flanges on said plate, and each of said
 spindles having at its inner extremity a head 115
 and a groove between said head and said
 worm; said grooves fitting into said notches
 on said head-stock; and pegs with gears there-
 on to engage with said worms on said spin-
 dles, substantially as described. 120

6. In a head-piece for stringed instruments,
 a plate bearing worm-gearing, and a head-
 stock to hold the inner extremities of said
 worm-gearing; said head-stock consisting of
 a channeled plate with notches therein to re- 125
 ceive the inner extremities of said worm-gear-
 ing, substantially as described.

7. A head-piece for a stringed instrument;
 said head-piece containing tuning-pegs per-
 pendicular to the upper face of said head-
 piece, and worm-gearing for actuating said
 pegs; and a central head-stock to retain the
 spindles which carry said worm-gearing; said 130
 head-stock consisting of a channeled plate

having perforations or notches on each side thereof; said head-piece being adapted to be placed upon the upper side of the head of said instrument, substantially as described.

- 5 8. The combination of a flanged plate, whose flanges are apertured to receive and form bearings for spindles bearing worms; spindles having said worms thereon, bearing at one end in said flanges, and having heads, and 10 grooves fitting into notches in a central head-stock on said plate; an additional plate apertured to receive tuning-peggs; pegs having gears at one extremity to engage with said

worms, and shoulders thereon of greater diameter than the apertures in said additional plate, so that said additional plate is clamped between said gears and shoulders on said pegs; apertures in said flanged plate to receive and fit said shoulders on said pegs; and a central head-stock having notches therein; 15 all substantially as described.
